C. P. CHAMBERLIN & C. T. FEZZEY,
DOUBLE COMPARTMENT PACKAGE FOR MAILING PURPOSES,
APPLICATION FILED APR. 18, 1914.

1,212,128.

Patented Jan. 9, 1917.

UNITED STATES PATENT OFFICE.

CLARENCE P. CHAMBERLIN AND CHESTER T. FEZZEY, OF DETROIT, MICHIGAN; SAID CHAMBERLIN ASSIGNOR TO SAID FEZZEY.

DOUBLE-COMPARTMENT PACKAGE FOR MAILING PURPOSES.

1,212,128.

Specification of Letters Patent.

Patented Jan. 9, 1917.

Application filed April 18, 1914. Serial No. 832,687.

To all whom it may concern:

Be it known that we, CLARENCE P. CHAMBERLIN and CHESTER T. FEZZEY, citizens of the United States, residing at Detroit, county 5 of Wayne, State of Michigan, have invented a certain new and useful Improvement in Double-Compartment Packages for Mailing Purposes, and declare the following to be a full, clear, and exact description of the 10 same, such as will enable others skilled in the art to which it pertains to make and use the same, reference being had to the accompanying drawings, which form a part of this specification.

15 This invention relates to combination container for mail matter and its object is a reinforced double compartment package for parcel-post and first class mail matter. Heretofore it has usually been the practice 20 to send small articles by parcel-post, while a letter referring to the mailing of such matter is sent in a separate envelop. Under a late ruling by the Postmaster General of the United States, parcel-post packages may 25 be sent attached to first class mail matter thus obviating the difficulties heretofore encountered by loss of one or the other of the packages. The particular novel features of 30 the invention are hereinafter more fully described and claimed and shown in the accompanying drawings in which—

Figure 1 is a view of the address side of the combined parcel-post and first class mail package. Fig. 2 is a perspective view of the 35 package ready for mailing. Fig. 3 is a view of the back of the combined package showing the reinforcement.

Similar characters refer to similar parts throughout the drawings and specification. 40 That part of the package designed for use in the transporting of parcel-post matter is preferably of the nature of a cloth tube 1, the outer open end 2 of which is provided with a cord 3 threaded through the material 45 by means of which the mouth of the tube may be drawn up and the ends of the cord wrapped thereabout and tied as shown in Fig. 2.

The envelop 4 for containing the first 50 class mail matter is preferably of a Manila or other comparatively stiff paper and the end 5 thereof is inserted in the end 6 of the cloth tube and secured in place thereon by a series of stitches passing through both sides 55 of the bag 1 and the envelop therebetween

which are preferably in the form of a rectangle as shown by dotted lines 7. The envelop is preferably reinforced with a cloth strip 10 that may be conveniently pasted to the back of the front or address side of the 60 envelop prior to its being folded in final form. This strip is preferably practically of the full width and length of the envelop within the interior thereof as indicated by dotted lines 11, and prevents the separating 65 of the envelop from the parcel-post package secured thereto.

By inserting the envelop some little distance in the cloth tube 1, as is shown in the drawing, the fabric is held comparatively 70 flat providing a convenient place for affixing the parcel-post stamps, and the bag has printed thereon a data indicating the position for the parcel-post postage, as well as the weight of the bag, while the envelop may 75 have indicated thereon the position for the first class postage. Both the envelop and the parcel-post package may have printed thereon the name and address of the sender as is usual with ordinary mail matter. 80

In addition to the function of holding the fabric flat to enable the parcel-post postage to be readily affixed thereto, the inserted end of the envelop and sewing thereof to the tubular fabric forms a closure for the 85 parcel-post package, the opposite end of which may be closed with a cord 3 as heretofore stated. Both the envelops and cloth container may be made in various sizes for various purposes. 90

The envelop 4 may also be of various forms having an opening on the side thereof sealed by the flap 8, as shown in Fig. 3, or by an end flap as shown by dotted line 9 in said figure, in which case the envelop would 95 open at the end opposite the end attached to the fabric. If a side flap is used as shown at 8, the envelop should be of greater length than the flap 8 providing a part to be inserted in the end of the tubular fabric. 100

Having thus briefly described our invention, what we claim and desire to secure by Letters Patent of the United States is—

1. A mailing package comprising a sealable envelop of itself forming a closed receptacle for first class mail matter, an open ended tubular cloth member sewed to the envelop at one end, the stitching serving to close an end of the tube and forming thereof a separate compartment for parcel post. 105 110

matter, and means for releasably closing the opposite end thereof.

2. A mailing package comprising an envelop having a gummed flap for the sealing thereof, a cloth container of tubular form, the envelop being partly inserted within an end of the cloth container and secured thereto, and a cord secured to the free end of the cloth container for closing the opening 10 thereof.

3. A package for mailing parcel-post and first class mail matter comprising a paper envelop having a cloth reinforcement secured thereto, and a cloth container forming a separate compartment for parcel-post matter sewed to the envelop, the stitching passing through both the envelop and reinforcement.

4. A package for mailing purposes comprising a paper envelop for first class mail matter, a cloth reinforcement secured within the envelop, and a cloth container for parcel-post mail matter sewed to the envelop, the stitching passing through both the envelop 25 and the reinforcement.

5. A double compartment package for

mailing purposes comprising a sealable envelop, a cloth container of tubular form, the envelop being partly inserted within an end of the cloth container and secured thereto 30 the envelop being of a width to hold the cloth container at the point of securing comparatively flat, and means for closing the open end of the cloth container.

6. A package for mailing purposes comprising a sealable envelop, a cloth reinforcement secured therewithin, a cloth container open at each end, an end of the envelop being inserted in an open end of the cloth container and stitched thereto, the opening in 40 the container being practically of the width of the envelop whereby the cloth of the container is held flat at the point of stitching, and means for closing the opposite end of the cloth container.

In testimony whereof, we sign this specification in the presence of two witnesses.

CLARENCE P. CHAMBERLIN,
CHESTER T. FEZZEY.
